POSITIVE ION TRAP GUN

David D. Van Ormer, Lancaster, Pa., assignor to Radio Corporation of America, a corporation of Delaware

Application September 16, 1954, Serial No. 456,361

12 Claims. (Cl. 313—76)

This invention is directed to a cathode ray tube and particularly to an electron gun structure providing a positive ion trap for use in cathode ray tubes such as television picture tubes.

Normally, a cathode ray tube for television or other purposes is one having an envelope with a large bulb portion and a tubular neck portion fixed thereto. Mounted within the tubular neck portion are a plurality of electrodes for forming and focusing an electron beam along a path extending into the bulb portion. Magnetic or electrostatic field producing means are used for moving the electron beam in any desired manner over a wall portion or face plate of the envelope bulb portion. The inner surface of the wall or face plate is coated with a film of phosphor material which luminesces with a visible light when struck by the electron beam. By modulating the current of the electron beam the scanned area of the phosphor screen can be varied in a manner to produce a light path in accordance with modulating signals applied to the electron gun of the tube.

Tubes of this type normally are highly evacuated. However, it has been found to be impossible to remove every trace of gaseous material from the tube envelope when it is sealed. Also, during the normal operating life of the cathode ray tube, certain occluded gases in the envelope wall or in other portions of the tube structure are caused to be released into the discharge space of the tube. The electron beam is normally accelerated at high energies between the cathode gun and the phosphor screen of the tube. The electron energies are sufficient to ionize gas particles which pass into the beam path during tube operation by knocking electrons out of the gas molecules forming positively charged gas ions. The accelerating fields within the gun structure of the tube act on the positively charged ion particles and urge them substantially along the electron beam path toward the negative end of the electron gun. The positive ions being accelerated to high energies will strike the cathode surface with sufficient energy to destroy the electron emitting properties of the cathode material on the electrode. Positive ion bombardment of the cathode surfaces in tubes of this type causes an early breakdown of the thermionic emission from the cathode surface. This deleterious effect on the cathode electrode greatly shortens the life of the cathode ray tube.

It is therefore an object of this invention to provide an electron gun for a cathode ray tube which includes means for preventing positive ion bombardment of the cathode surface.

It is another object of the invention to provide a novel electron gun means which includes structure for trapping positive ions formed in the electron beam path.

It is a further object of this invention to provide an electron gun for television picture tubes which includes means for preventing positive ions in the beam path from striking the cathode.

The invention is a novel electron gun structure in which the beam-forming electrodes of the gun are offset

2

from the normal axis to the phosphor screen surface or are offset from the undeflected beam path directed at the phosphor screen. The beam-forming electrodes of the gun establish an electron beam which is accelerated toward the screen axis into a non-symmetric electron lens which bends the beam to align it with the screen axis normal to the screen at its center. The positive ions which in the absence of the invention would bombard the cathode surface are only those which are formed in the beam path outside of the field-free regions of the tube. These positive ions will normally be different in energy than the energy of the electrons and the negative ions of the beam and upon passing back down the beam path toward the cathode electrode, these positive ions because of their difference in energy will be bent out of the beam path by the electrostatic bending field and will be collected by portions of the beam-forming electrodes of the gun.

Figure 1 is a sectional view of the cathode ray tube having a gun structure in accordance with the invention.

Figure 2 is a schematic representation of the beam path of the gun of Fig. 1.

Figure 3 is a cross-sectional view of another form of the invention.

The cathode ray tube envelope of Fig. 1 comprises a large bulb portion 10 and a tubular neck portion 12 which is substantially a cylinder of glass formed with its axis 14 coincident with the axis of the bulb portion 10. The end of the bulb portion 10 opposite to the tubular neck 12 consists of a glass wall portion or face plate 16 upon which is formed a film or coating 18 of finely divided phosphor particles, which forms a phosphor screen.

Mounted within the tubular envelope portion 12 is an electron gun 20 consisting of a cathode electrode 22 mounted within an enclosing tubular control grid electrode 24. Closely spaced from the control grid 24 and axially aligned therewith is a short cup-shaped tubular accelerating electrode 26. The electrodes 22, 24 and 26 are aligned on a common axis which makes a small angle with the axis 14 of the tubular neck 12.

Mounted coaxially within the tubular neck 12 is a second accelerating electrode 28 consisting of a tubular metal member closed at one end by a circular plate structure 30 having a centrally located aperture 32 therein. Electrodes 24 and 26 are closed by centrally apertured plate structures 34 and 36 respectively. The apertures of these plates 34 and 36 are aligned and are located on a common axis of the electrodes 24 and 26. The adjacent ends of the electrodes 26 and 28 are cut at an angle both to the axis 14 of electrode 28 and the common axis of electrodes 22, 24, and 26. The centrally located aperture of plate 34, of control grid 24 overlies one end of the cathode 22 which is closed by a solid wall portion, the outer surface of which is coated with an electron emitting material.

The apertured plate 30 of the electrode 28 is connected by spring fingers 38 to a conductive coating 40 formed on the inner surface of the tubular neck 12 and which extends from the neck 12 into the bulb portion 10 to a point adjacent the fluorescent screen 18. The electrodes of the electron gun 20 are mounted in their spaced position and are insulated from each other by ceramic or glass support rods, which are not shown.

Operative potentials are applied to the several electrodes shown, by connecting these electrodes with conductive leads 42, sealed through a glass wall portion 44 closing the end of the tubular neck 12. Leads 42 are connected respectively to pins 46 extending externally of the tube envelope from a base portion 48. During operation, the cathode cylinder 22 and its coated end portion is heated by a heater filament to a sufficiently high temperature to cause an electron emission from the

coated cathode surface. Voltages are applied to the several electrodes having values of the order of those indicated in Fig. 1. These potential values are not limiting but are illustrative of voltages which have been used in tubes of the type shown in Fig. 1 and for the purposes to be described.

In operation, electrons emitted from the coated cathode surface are urged through the apertured grid plate 34 by the accelerating field of electrode 26 and are formed into an electron beam 50 directed along the common axis of electrodes 24 and 26. Potentials on electrodes 26 and 28 form an electron lens field therebetween. Because the adjacent ends of electrodes 26 and 28 lie in parallel planes tilted at an angle to the common axis of electrodes 24 and 26 and also at an angle to the axis 14 of electrode 28, the lens field formed between electrodes 26 and 28 is non-symmetric with respect to these two axes. Therefore, the electron beam 50 passing along the axis of electrodes 24 and 26 passes into this lens field at an angle thereto and is bent toward the axis of the lens field which may be considered substantially normal to the parallel planes in which lie the adjacent ends of electrodes 26 and 28. The potential difference between electrodes 26 and 28 can be adjusted to control the amount of deflection or bending which the non-symmetric lens field gives to electron beam 50. During tube operation the electron beam is bent to align the beam on axis 14 and directed substantially normal to the fluorescent screen 18 at its center. The angle which the adjacent ends of electrodes 26 and 28 make with axis 14 may also be varied to provide the desired amount of beam bending for the voltage ranges used on electrodes 26 and 28.

In a successfully operated tube of the type described, the adjacent ends of electrodes 26 and 28 are formed at an angle of substantially ten degrees to axis 14. The electron beam in passing through the non-symmetric lens between electrodes 26 and 28 is given its final and greatest acceleration so that in passing down the axis 14 of electrode 28 the electron beam is moving with high energy into a field-free space which extends from a point within tubular electrode 28 to the screen, since electrode 28 and the conductive coating 40 are maintained at a common potential.

The electron beam 50 passing into the non-symmetrical field between electrodes 26 and 28 is a divergent beam. The non-symmetrical field, provides only a small convergence to the beam so that the beam striking apertured plate 30 is still somewhat divergent. A magnetic field provided by a coil winding 52 is used to focus the electron beam to a small spot on fluorescent screen 16. Coil 52 is enclosed in an iron armature casing 54 to provide a concentrated focusing field on the tube axis 14. The electron beam 50 is scanned over the surface of target screen 18 by deflecting magnetic fields formed by pairs of deflecting coils mounted in a neck yoke 56 on the tubular neck portion 12. These deflecting coils consist of pairs of coils connected in series to sources of sawtooth currents for providing respectively line and frame scansion of the electron beam. Both the focusing means 52 and the deflecting means 56 are conventional and do not constitute a part of this invention. Accordingly, they are not described in greater detail.

The scansion of beam 50 of screen 18 may be in any well known manner such as to provide for example a rectangular raster normally used in television picture tubes. The intensity of electron beam 50 is normally varied in accordance with signal voltages applied to the control grid 24. Thus the beam 50 can be modulated in accordance with video signals applied to screen 24 to provide a charge pattern of light on the fluorescent screen 18, such as a television picture.

In tubes of the type described and shown in Fig. 1, it is desirable that the tube envelope be completely evacuated for optimum operation. Traces of gas within the

tube envelope provide a source of positive ions when struck by the high energy electrons and negative ions of beam 50. Since these ions are positively charged they pass down the electron beam path 50 and are accelerated by the electrostatic fields along the path to strike the cathode electron emitting surface at high energies. Positive ion bombardment of the cathode surface causes a deterioration of the emitting characteristics of the coating and tend to greatly shorten the life of the discharge tube.

Therefore, in accordance with the invention, the cathode 22 is offset from the tube axis 14 and a non-symmetric electrostatic lens is formed along the beam path between the cathode 22 and screen 18 and at the portion of the beam path at which the electron beam has its greatest energy.

Fig. 2 is an enlarged schematic representation of the electron beam path 50 extending from cathode 22 into the tubular electrode 28. In describing the invention it is only necessary to consider the effect of those positive ions formed along the electron beam path by the direct collision of electrons and negative ions of the electron beam with gas molecules present in the beam path, since it is only those positive ions formed by direct collision which will pass back down the beam path to the cathode. Positive ions formed by other than direct collision with electrons or negative ions will be deflected away from the beam path and will be collected by electrode structures of the gun 20.

A direct collision between a gas molecule and a negative beam particle will give the positive ion formed an initial motion along the beam path in the direction of the screen 18. Considering the positive ions formed within the electrode cylinder 28 between the bending lens field and screen 18, if an ion is formed by direct collision within electrode 28, at point A (Fig. 2) it may receive sufficient energy to force the positive ion toward screen 18 and into the field-free space extending from within electrode 28 to screen 18. This positive ion is thus carried out of any accelerating field and will not be drawn back along the beam path 50 to the cathode 22.

A positive ion formed by direct collision with a negative particle at point B within electrode 28 will be first forced by the action of the collision along the beam path toward screen 18, but because of the accelerating negative fields between point B and the cathode 22, the energy of collision will be insufficient to carry the positive ion into the field free space, but instead will cause the ion to reverse the direction of its motion and to be accelerated back along the beam path 50. As the positive ion passes the point of collision, B, it will have gained the energy of formation and will be further accelerated to enter the deflecting field between electrodes 26 and 28 at a higher energy than the energy of the electron beam passing through the deflecting field in the opposite direction. That is, the positive ion will enter the deflecting field with substantially all of the energy imparted to it at collision in addition to the energy given to the positive ion by the high accelerating field between electrodes 26 and 28. Since the deflection of a moving charged particle by an electric field is inversely proportional to the kinetic energy of that particle, positive ions passing into the deflecting field between electrodes 26 and 28 will not follow the electron path to the cathode surface, since due to their inherently greater energy they will be deflected less than the electrons of the beam following the path 50. Thus, these high energy positive ions will not pass through the aperture of plate 36 but will be collected thereby and thus be prevented from striking the coated surface of cathode 22.

Positive ions formed by direct collision in the deflecting region, between electrodes 26 and 28, at points C and D for example, and at other points with sufficient energy to carry them into this field, will be deflected by

the non-symmetric field oppositely to the electron beam and will be randomly scattered. Positive ions, however, formed between the cathode and the deflecting field at E, for example, with insufficient energy of formation to drive them to the deflecting field will be returned to the cathode. However, positive ions formed within this region (at E) are formed at low energies and since they are not accelerated to high energies due to the low potential difference between electrode 26 and cathode 22, the positive ions in this region will strike the cathode surface at relatively low energy. To provide complete trapping of the positive ions within this region between the cathode and the deflecting field, it would be necessary to maintain the positive potential of electrode 26 below the ionizing energy of the gas molecules present, and thus prevent the negative ions or electrons of the beam, accelerated by electrode 26 in this region, from having an ionizing effect on gas molecules in the beam path.

An alternative structure which would provide trapping of positive ions in the low potential field adjacent to the cathode electrode is schematically shown in Figure 3. This figure discloses a neck portion 70 of a cathode ray tube and corresponding in structure to the neck portion 12 of Figure 1. Mounted within the neck 70, by any appropriate means (not shown), is an electron gun structure 71. The gun structure 71 consists of a conventional cathode electrode 72 insulatingly mounted on a ceramic disc 74 within a tubular control grid electrode 76. Control grid 76 includes an end wall 75 spaced from one end of cathode 72 which is closed and coated with electron emitting material. Cathode 72 and control grid 76 are coaxially arranged along a common axis 73 making substantially a 45° angle with the axis 78 of the tubular neck portion 70. An accelerating electrode 80 includes a plate portion 82 overlying and spaced parallel to the end wall portion 75 of control electrode 76. Spaced from electrode 80 is a second accelerating tubular electrode 84 coaxially mounted on the axis 78 of the tubular neck 70.

Control grid end wall 75 and accelerating electrode plate 82 each have apertures therethrough substantially at their centers and overlying the coated end of cathode 72. The apertures in plate portions 75 and 82, however, are offset from each other or staggered, the aperture of plate 75 being on axis 73 and the aperture in plate 82 being slightly displaced from axis 73 in a direction away from the axis 78. Electrode 80 may have a portion 86 extending from plate 82 to a point spaced from the adjacent end of tubular electrode 84, substantially as shown.

To operate the gun structure of Figure 3, appropriate voltages are applied in the order of the values disclosed for corresponding electrodes of Figure 1. Cathode 72 is heated by a filament (not shown) to a thermionic temperature. Electrons are emitted from the heated cathode electrode 72 and are accelerated by electrode plate 82 through the offset apertures in adjacent plates 75 and 82. Because of the offset arrangement of these apertures, the electrostatic field between electrode portions 75 and 82 form an asymmetric electron lens which bends the electrons away from axis 73 and along a path which coincides with axis 78, as the beam enters the accelerating electrode 84. The electron beam is thus directed down the tube axis 78 by the accelerating lens field as described above for Fig. 1. The beam then may be focused and scanned over a fluorescent screen in the manner described above for the structure of Fig. 1.

The gun structure of Fig. 3 provides a bending field which extends through the aperture of grid plate 75 into the region adjacent to the cathode electrode 72. This bending field includes portions of the accelerating field of plate 82 which are below the ionization energies of gases. The negative particles of the beam passing through the negative grid aperture of plate 75 are accelerated only by the asymmetric field of the off-set

apertures. Positive ions formed in the region between plates 75 and 82 will thus be in an accelerating bending field. These positive ions will normally have a different energy than the negative particles in the electron beam so that when they are urged toward the cathode 72, they will be bent differently by the asymmetric field and will pass out of the electron path to be captured by adjacent electrode portions. Also, positive ions formed in the bending field between plate 82 and electrode 84, will also be deflected off of the electron path as described above for the structure of Fig. 1. Thus, all points of the beam path between cathode 72 and the final accelerating electrode 84, and where the negative particles of the beam reach ionizing energies, will be within the beam bending field. The structure then of Fig. 3 discloses a means for a complete trapping of all positive ions formed between the cathode and the phosphor screen of the cathode ray tube.

As pointed out above, the positive ions formed along the electron beam path are trapped by the structure disclosed. The elimination of these positive ions eliminates the deleterious ion bombardment of the cathode surface, and thus results in a longer cathode life to extend the operational life of the cathode ray tube. The trapping of the positive ions is effectively done by a non-symmetric electrostatic beam bending field between the cathode electrode and the point of formation of the positive ions.

What is claimed is:

- 30 1. An electron gun for forming a beam of negative particles along a path, said electron gun including an accelerating electrode aligned on an axis along said beam path, a cathode electrode spaced from said accelerating electrode and offset in one direction from said axis for providing an electron emission, and tubular electrode means along said beam path between said cathode and accelerating electrode for providing an electrostatic field lens for bending said beam in said one direction to align said beam with said axis.
- 20 2. An electron gun for forming a beam of negative particles along a path, said electron gun including a first accelerating electrode aligned on an axis along said beam path, a cathode electrode spaced from said accelerating electrode and offset in one direction from said axis, and a tubular second accelerating electrode adjacent to said first accelerating electrode and between said first accelerating electrode and said cathode electrode, said second accelerating electrode being axially aligned with said cathode electrode and offset in said one direction from said axis for providing an electrostatic field lens for bending said beam in said one direction to align said negative beam with said axis.
- 30 3. An electron gun for forming a beam of negative particles along a path, said electron gun including a first accelerating electrode aligned on an axis along said beam path, a cathode electrode spaced from said accelerating electrode and offset in one direction from said axis, and a tubular second accelerating electrode mounted adjacent to said first accelerating electrode and between said first accelerating electrode and said cathode electrode, said tubular second accelerating electrode being axially aligned with said cathode electrode and offset in said one direction from said axis, the adjacent ends of said first and second accelerating electrodes lying in parallel planes disposed at an angle to said axis for bending said beam in said one direction to align said beam along said axis.
- 40 4. An electron gun for forming a beam of negative particles along a path, said electron gun including an accelerating electrode aligned on an axis along said beam path, a cathode electrode spaced from said accelerating electrode and offset in one direction from said axis, and electrode means along said beam path between said cathode and accelerating electrodes for providing an electrostatic field for bending said beam in said one direction to align said negative beam with said axis, said electrode
- 50
- 60
- 70
- 80
- 90

means including a pair of parallel plates each having an aperture therethrough, said apertures being offset from each other relative to said axis.

5. An electron discharge device comprising an electron gun for forming a beam of negative particles along a path, said electron gun including an accelerating electrode aligned on an axis along said beam path, a cathode electrode spaced from said accelerating electrode and offset in one direction from said axis, and electrode means along said beam path between said cathode and accelerating electrodes for providing an electrostatic field aligning said negative beam with said axis, said electrode means including a pair of electrode members each having an aperture therethrough, said apertures being positioned in line with a portion of said cathode emitting surface and offset from each other relative to said axis for bending said negative beam in said one direction to align said beam along said axis.

6. A cathode ray tube comprising an envelope having a tubular portion, a fluorescent screen within said envelope, an electron gun structure spaced from said screen and including a cathode electrode within said tubular envelope portion for producing a beam of electrons along a path offset in one direction from the axis of the tubular envelope portion wherein positively charged ions may be present in said electron beam, means between said cathode electrode and said screen for providing an electrostatic field for bending said electron beam in said one direction to align said electron beam with said tubular envelope axis.

7. A cathode ray tube comprising an envelope having a tubular portion, an electron gun structure including a cathode electrode within said tubular envelope portion for producing a beam of electrons along a path offset in one direction from the axis of the tubular envelope portion wherein positively charged ions may be present in said beam, said electron gun structure including as a part thereof means for forming a non-symmetric electrostatic field in the path of said beam for bending said electron beam in said one direction to align said beam with said tubular envelope axis.

8. A cathode ray tube comprising an envelope having a tubular portion, an electron gun structure including a cathode electrode within said tubular envelope portion and offset in one direction from the axis thereof for producing a beam of electrons along a path wherein positively charged ions may be present in said beam, said electron gun structure including as a part thereof means for forming a non-symmetric electrostatic field in the path of said beam for bending said beam in said one direction to align said beam with said tubular envelope axis, said means including a tubular electrode coaxially mounted within said tubular envelope portion and a second electrode adjacent to said tubular electrode and mounted between said tubular electrode and said cathode electrode, adjacent portions of said tubular and second electrodes lying in parallel planes tilted in said one direction and at an angle to said axis, said electron gun structure including impermeable structure closely spaced from said beam path for collecting positive ions directed toward said cathode.

9. A cathode ray tube including an electron gun for forming a beam of negatively charged particles in which positive ions may be present, said electron gun including a cathode electrode having an electron emitting

surface and a pair of electrodes each having an aperture overlying said cathode surface, an accelerating electrode having a centrally disposed aperture therethrough and mounted on an axis through said centrally disposed aperture, said pair of electrodes being fixed so that a straight line from said cathode emitting surface passes through the apertures of said pair of electrodes at an angle to said axis, the apertures of said pair of electrodes being offset from each other relative to said straight line.

10 10. The method of separating positive ions from the negative particles of a cathode ray beam within a cathode ray tube including a cathode electrode and a fluorescent screen, said method comprising the steps of forming the negative particle beam along a path offset from a second path directed at the phosphor screen, using an electrostatic lens field non-symmetrically disposed with said beam path to align said negative particle beam with said second beam path, collecting the positive ions which are separated from the negative particle beam by the non-symmetrical electrostatic lens before the positive ions strike the cathode.

11. The method of separating positive ions from the negative particles of a cathode ray beam within a cathode ray tube including a cathode electrode and a fluorescent screen, said method comprising the steps of forming electrons from said cathode into a beam which may contain other negative particles and which is displaced from the axis substantially normal to said fluorescent screen at its center, directing said negative beam along a path toward said axis through an electrostatic lens field asymmetrically disposed relative to said beam path and said axis, adjusting the strength of said asymmetric field to align said negative beam with said axis.

held to align said negative beam with said axis.

12. The method of separating positive ions from the negative particles of a cathode ray beam within a cathode ray tube including a cathode electrode and a fluorescent screen, said method comprising the steps of, forming electrons from said cathode into a beam which may contain other negative particles and which is displaced from the axis substantially normal to said fluorescent screen at its center, directing said negative beam along a path toward said axis through an electrostatic lens field asymmetrically disposed relative to said beam path and said axis, adjusting the strength of said asymmetric field to align said negative beam with said axis, collecting positive ions separated by the asymmetric lens from the negative particle beam before the positive ions strike the cathode electrode.
